UNITED STATES PATENT OFFICE.

CHARLES MARIUS MOTTE, OF PARIS, FRANCE.

PROPELLER FOR VESSELS.

Application filed March 22, 1921. Serial No. 454,569.

To all whom it may concern:

Be it known that I, CHARLES MARIUS MOTTE, a citizen of the French Republic, residing at Paris, France, have invented new and useful Improvements in Propellers for Vessels, of which the following is a specification.

In the specification accompanying my co-pending application filed on April 12, 1920, Serial No. 373,361 for "propellers for vessels," which has matured into Patent No. 1,408,765, a suspended turbine is described which carries the turbine wheel in a completely surrounding casing having top and bottom admission and lateral eduction.

The object of my present modification is to provide a vertically displaceable suspended turbine for use in pinnaces or chalanas and like flat-bottomed vessels that have to navigate in shallow waters, and I attain this object by the arrangement hereinafter described with reference to the annexed drawings, in which:

Figures 1 and 2 are vertical sections showing the lowered and raised position of the turbine;

Fig. 3 a corresponding plan;

Fig. 4 a rear elevation of a complete installation;

Fig. 5 a vertical section drawn to a larger scale, of the turbine;

Figs. 6, 7 and 8 are diagrams, drawn in plan, showing various positions of the eduction port of the turnable turbine casing.

The turbine wheel *a* revolves in the casing *b* having admissions *b*¹, *b*² and a lateral eduction *d*. A perforated hood *l* keeps the turbine free from sludge and objectionable matter. *c* denotes the turbine shaft and *e* the

sleeve carrying and turning the casing *b*. A stationary housing or well *j* covering the turbine, is fixed in the pinnace in watertight manner and communication channels *m* and *n* lead from the housing through cor-

responding ports in the sides of the pinnace or chalana. A power shaft *u* rotates a pinion *t* which gears with a wheel *s* keyed to the turbine shaft *c*. This mechanism is enclosed in a box *q* adjustably held by a screw-

spindle *p* controlled by a handwheel *o*, the whole being mounted in a standard *r*. To turn the turbine casing in steering the boat, I provide mitre wheels *v* from one of which a spindle *w* descends along-side the box *q*.

The spindle *w* has gear-teeth *x* to be in constant mesh with a pinion *y* which turns the wheel *z* fast on the sleeve *e* connected with the casing *b*, which latter can be turned angularly and also lifted and lowered. To permit of lifting and lowering the mechanism without disconnecting same from the motor, the driving shaft can consist of two parts having universal joints to enable them to be coupled to a train of gear wheels, actuated by the motor, and to the pinions *t* in gear with the wheels *s*.

When the pinnace, or chalana, is empty and the water duct *m* is above the water level it will be necessary to lower the turbine with its hood *l* below the flat bottom of the boat as shown in Figs. 1 and 4 so that now the water is admitted to the turbine through the perforated sides *l* of the hood. With loaded pinnace, the turbine is brought up as shown in Figs. 2 and 5, when *m* becomes the admission and *n* the eduction.

I claim—

A turbine apparatus, for propelling and steering a vessel having a well for the turbine provided with inlet and discharge openings, comprising a turbine wheel; a vertical shaft at the bottom of which the wheel is secured; a casing for the wheel having inlet and discharge openings adapted to communicate with the openings in the well; a perforated hood carried by the casing; a sleeve surrounding the shaft secured to the casing; gear means for driving the shaft at the upper end thereof; a housing for the driving means adapted to rotatably support the upper end of the sleeve; a standard fixed on the well; a screw spindle secured to the gear housing and extending through the standard; a screw threaded hand wheel seated on the standard and engaging the screw spindle to adjust the turbine vertically within the well, and means for rotating the sleeve and turbine casing to vary the angular relation of the discharge opening therein comprising a system of gears, one of said gears being elongated and mounted on said well and standard and the others of said gears being carried by the gear housing and sleeve whereby rotation of the sleeve and turbine casing is permitted at any vertical position thereof.

CHARLES MARIUS MOTTE.
